SINGLE DRUM REWINDER OR SIMILAR ARTICLE

Gerald H. Zimmerman and Edward J. Klaczkiewicz, Wilmington, Del., assignors to Beloit Eastern Corporation, Downingtown, Pa., a corporation of Delaware

Filed Mar. 27, 1963, Ser. No. 74,156

Term of patent 14 years

(Cl. D55—1)

The dominant features of our design reside in those features shown in full lines. The paper roll on the spindle shown in dot-dash lines and appearing to the left in FIGURE 1 and to the right in FIGURE 2 is included for illustrative purposes only. The inner surfaces of each of the ends of the winder, which are not shown, are substantially plain.

We claim:

The ornamental design for single drum rewinder or similar article, as shown and described.
